Specification for Design.

Patented Apr. 26, 1921.

Application filed September 20, 1920. Serial No. 411,668. Term of patent 3½ years.

To all whom it may concern:

Be it known that I, JOSEPH GIAMMARINO, a citizen of the United States, residing at New York city, in the county of Bronx and State of New York, have invented a new, original, and ornamental Design for Wall-Plates for Mounting Electric Arms, of which the following is a specification, reference being had to the accompanying drawings, forming part thereof.

Figure 1 is a plan view of a wall plate showing my new design;

Fig. 2 is a side elevation in outline thereof; and

Fig. 3 is a transverse section on the line 3—3 of Fig. 1.

I claim:

The ornamental design for a wall plate for mounting electric arms, as shown.

JOSEPH GIAMMARINO.
